JAMES R. KILLEN, OF DAYTON, OHIO, ASSIGNOR TO FRIGIDAIRE CORPORATION, OF DAYTON, OHIO, A CORPORATION OF DELAWARE

REFRIGERATING APPARATUS

Application filed April 30, 1930. Serial No. 448,540.

The present invention relates to refrigerating apparatus and particularly to evaporators.

One of the objects of the present invention is to provide an improved evaporator of the type which is relatively long horizontally and relatively narrow vertically.

Another object of the invention is to provide a relatively long and relatively narrow evaporator of the flooded type in which it is necessary to use only a comparatively small amount of liquid refrigerant.

A further object is to prevent oil logging of horizontally extending ducts of a flooded type evaporator and to prevent liquid refrigerant from passing from the evaporator.

More specifically it is an object of the present invention to provide for a free space directly above the liquid refrigerant throughout the length of an elongated evaporator of the flooded type.

Further objects and advantages of the present invention will be apparent from the following description, reference being had to the accompanying drawing, wherein a preferred form of the present invention is clearly shown.

In the drawing:

Fig. 1 is a rear view of a display type of refrigerator, partly in section, the section being taken on line 1—1 of Fig. 2 and showing my improved evaporator therein;

Fig. 2 is a sectional view taken on line 2—2 of Fig. 1;

Fig. 3 is a top plan view of the improved evaporator;

Fig. 4 is a side view thereof; and

Fig. 5 is a sectional view taken on line 5—5 of Fig. 4.

The present invention deals principally with evaporators that are relatively long horizontally and relatively narrow vertically and the particular evaporator, shown for illustrative purposes only, is illustrated in connection with a display case having a relatively long horizontal and relatively narrow vertical cooling chamber or compartment. In the specific embodiment the display case comprises a cabinet 20 having an upper food

storage compartment 21 and a lower compart-

ment 22. In the latter certain parts of refrigerating apparatus may be enclosed or it may be used for a storage chamber. At the lower part and to the rear of the storage compartment 21 there is provided a cooling chamber or compartment 24 for receiving the evaporator 25. This evaporator is supported on brackets 26 so as to provide a space below same and is proportioned so as to be spaced from the upper part of the compartment 24. A baffle 28 causes the air which enters the compartment 24 to circulate through the evaporator before it leaves the compartment.

The evaporator is of the flooded type and is herein shown as the type in which the quantity of refrigerant therein is controlled by a float on the low pressure side of the system. Referring particularly to Fig. 4, the evaporator comprises a header or tank 30 form a reservoir for liquid refrigerant. Liquid refrigerant is led to the evaporator through a coupling 31 and is withdrawn therefrom through a coupling 32. These couplings are carried by a removable head 33. The flow of refrigerant from a condenser of the refrigerating system through the coupling 31 and into the header 30 is controlled by a float 34 contained within the header 30. This float actuates a needle valve 35 to prevent further flow of liquid refrigerant into the evaporator when a predetermined liquid level is attained within the header. The outlet of the header is in the form of a tube 37 which extends into the header and is connected with coupling 32. In order to provide a relatively long horizontal heat absorbing surface without using a large quantity of liquid refrigerant, I extend duct means from the end 38 of the header 30 and connect fin means thereto for increasing the heat transfer surface thereof. In the particular embodiment I have shown two flattened ducts 40 of sheet metal, preferably of copper, which are secured to the end of the header in a suitable manner as by soldering. These flattened ducts provide tall narrow refrigerant chambers and the arrangement is such that the liquid refrigerant is below the upper part of the tall duct so as to provide a gas chamber or free space

above the liquid in the ducts. The ends of ducts, opposite the header 30, are sealed as at 41.

In addition to increasing the heat transfer surface of the ducts 40, the fins 43 increase the strength of the evaporator. The ducts 40 being tall and narrow will tend to bulge outwardly when an excessive pressure is present within the evaporator. In the particular arrangement the ducts 40 extend through slots within the fins 43 and these slots are substantially the same dimensions as the outside dimensions of the tube. These fins are preferably soldered to the duct so as to closely embrace the ducts and thereby prevent bulging of same and so as to provide a good heat transfer relation between same. Due to the shape of the ducts, a comparatively small amount of refrigerant is brought in contact with a relatively large heat transfer section of transversely disposed fins.

In refrigerating systems of the type in which oil floats upon the refrigerant within the evaporator, for example, when SO_2 is used as a refrigerant, this oil tends to collect in certain places and prevent the flow of refrigerant whereby some portions of the evaporator do not function properly. Also the oil tends to form in a thick blanket upon the refrigerant and causes what is known as "bumping" within the evaporator namely, the blanket prevents the boiling of the refrigerant until the refrigerant is super-heated and then an explosion takes place within the evaporator. Under such conditions, liquid refrigerant will be conveyed out of the evaporator causing refrigeration to take place in the outlet pipe of the evaporator and at times causes liquid refrigerant to be delivered to the compressing mechanism. In accordance with the present invention, I prevent the collection of a thick blanket of oil on the refrigerant by providing a free surface for the escape of gas throughout the length of the evaporator. This free surface is indicated at 44 above the oil level 45. The liquid refrigerant level is shown at 46. By this arrangement the gas bubbles may flow in their natural manner namely, upwardly, and due to the constant ebullition, a quantity of oil is carried with the gas bubbles into the free space whence it is delivered through the outlet 37 to the compressor. By constantly withdrawing a quantity of oil with the gas only a small layer of oil will collect upon the evaporator.

In addition to the advantages above set forth the evaporator herein disclosed can be manufactured at a low cost since it can be readily assembled because of the necessity of only a few tubes and only a few soldered joints.

While the form of embodiment of the invention as herein disclosed, constitutes a preferred form, it is to be understood that other

forms might be adopted, all coming within the scope of the claims which follow.

What is claimed is as follows:

1. An evaporator for a mechanical refrigerator comprising a reservoir for liquid refrigerant, a tall narrow refrigerant duct extending horizontally from the reservoir, said duct having its lower portion connected below the liquid refrigerant level and its upper portion with the free space above the liquid, and fin means thermally connected with said duct. 70

2. An evaporator for a mechanical refrigerator comprising a reservoir for liquid refrigerant, a tall narrow refrigerant duct extending horizontally from the reservoir, said duct having its lower portion connected below the liquid refrigerant level and its upper portion with the free space above the liquid, and a plurality of fins arranged transversely 80 of said duct and thermally connected therewith. 85

3. An evaporator for a mechanical refrigerator comprising a reservoir for liquid refrigerant, a tall narrow refrigerant duct extending horizontally from the reservoir, means for maintaining the refrigerant level intermediate the top and bottom of said duct, and fin means thermally connected with said duct. 90 95

4. An evaporator for a mechanical refrigerator comprising a reservoir for liquid refrigerant, a tall narrow refrigerant duct extending horizontally from the reservoir, means for maintaining the refrigerant level intermediate the top and bottom of said duct, and a plurality of fins arranged transversely 100 of said duct and thermally connected therewith. 105

5. An evaporator for a mechanical refrigerator comprising a reservoir for liquid refrigerant, a plurality of tall narrow refrigerant ducts extending horizontally from the reservoir, said ducts each having its lower portion connected below the liquid refrigerant level and its upper portion with the free space above the liquid, and fins connected with said ducts and bridging the space between same. 110

6. An evaporator for a mechanical refrigerator comprising a reservoir for liquid refrigerant, a plurality of tall narrow refrigerant ducts extending horizontally from the reservoir, said ducts each having its lower portion connected below the liquid refrigerant level and its upper portion with the free space above the liquid, and a plurality of fins arranged transversely of said ducts, said fins being thermally connected with said ducts and bridging the space between same. 115 120 125

7. An evaporator for a mechanical refrigerator comprising a reservoir for liquid refrigerant, a plurality of tall narrow refrigerant ducts extending horizontally from the reservoir, means for maintaining the refrigerant level and its upper portion with the free space above the liquid, and a plurality of fins arranged transversely of said ducts, said fins being thermally connected with said ducts and bridging the space between same. 130

erant level intermediate the top and bottom of said ducts, and fins connected with said ducts and bridging the space between same.

8. An evaporator for a mechanical refrigerator comprising a reservoir for liquid refrigerant, a plurality of tall narrow refrigerant ducts extending horizontally from the reservoir, means for maintaining the refrigerant level intermediate the top and bottom of said ducts, and a plurality of fins arranged transversely of said ducts, said fins being thermally connected with said ducts and bridging the space between same.

9. An evaporator for a mechanical refrigerator comprising a reservoir for liquid refrigerant, a tall, narrow refrigerant duct extending horizontally from the reservoir, and means for maintaining the refrigerant level intermediate the top and bottom of said duct, said duct having a relatively large contacting surface in proportion to the volume of refrigerant contained therein.

10. An evaporator for a mechanical refrigerator comprising a reservoir for liquid refrigerant, a plurality of tall, narrow refrigerant ducts extending horizontally from the reservoir, said ducts each having its lower portion connected below the liquid refrigerant level and its upper portion with the free space above the liquid, said ducts having a relatively large amount of contacting surface in proportion to the volume of refrigerant contained therein.

11. An evaporator comprising a plurality of horizontally extending, tall, narrow and parallel ducts, each duct having parallel upright sides, a fin means bridging all of said ducts, said fin means being arranged substantially perpendicular to and in a plane transverse to the longitudinal axis of the ducts.

12. An evaporator comprising a plurality of horizontally extending, tall, narrow and parallel refrigerant conveying ducts, a plurality of strip fins, each fin bridging all of said ducts, said fins being arranged substantially perpendicular to and in a plane transverse to the longitudinal axis of the ducts.

13. In combination with a refrigerator designed for the circulation of air in a given direction, an evaporator located within said refrigerator, said evaporator comprising a plurality of tall, narrow and parallel refrigerant conveying ducts, a plurality of strip fins, each fin bridging all of said ducts, said evaporator being arranged within said refrigerator so that the fins are parallel to the path of circulating air within the refrigerator and said fins being also substantially perpendicular to and in a plane transverse to the longitudinal axis of the ducts.

In testimony whereof I hereto affix my signature.

JAMES R. KILLEN.
